UNITED STATES PATENT OFFICE.

CHRISTIAN DORN, OF PHILADELPHIA, PENNSYLVANIA, ASSIGNOR OF ONE-HALF TO WILLIAM GEORGE T. MARCELLUS, OF SAME PLACE.

DASH-POT VALVE.

SPECIFICATION forming part of Letters Patent No. 619,680, dated February 14, 1899.

Application filed July 14, 1898. Serial No. 685,940. (No model.)

To all whom it may concern:

Be it known that I, CHRISTIAN DORN, a citizen of the United States, residing at Philadelphia, in the county of Philadelphia and State of Pennsylvania, have invented certain new and useful Improvements in Dash-Pot Valves for Steam-Engines; and I do hereby declare the following to be a full, clear, and exact description of the invention, such as will enable others skilled in the art to which it appertains to make and use the same.

My invention relates to improvements in valves for steam-engines, and particularly to valves for regulating the action of dash-pots on steam-engines; and it consists of the novel construction hereinafter described and claimed.

Reference is had to the accompanying drawings, wherein the same parts are indicated by the same letters throughout both views.

Figure 1 represents a central vertical sectional view of my improved form of regulating-valve, and Fig. 2 is a section taken on the line 2 of Fig. 1 and looking in the direction of the arrow.

A represents the body of the valve, having the enlarged chamber A⁰ and screw-threaded connection A¹. At one side—that is to say, at the top of the chamber A⁰—the valve-body A is provided with a smaller connection A², and at the opposite side—that is to say, at the bottom—an enlarged neck A³, provided with screw-threaded connection A⁴, extends away from the body of the valve in a direction opposite to that of the connection A². This enlarged neck A³ has a hollow chamber A⁵ in its base, and at its inner end has a bridge A⁶, provided with a central enlargement A⁷, which constitutes a stop for the valve B, hereinafter referred to. Within this chamber A⁵ is located a ball-valve B, and a screw-plug B', provided with axial opening B⁰, is fitted into the screw-threaded connection A⁴ and has its inner end hollowed out, as at b⁰, to form a seat for the ball-valve B, the said inner end of the screw-plug extending a short distance into the chamber A⁵, as shown in the drawings. A lock-nut C, having an ear or lug C' thereon adapted to be struck by a hammer for loosening or tightening said lock-nut, is fitted upon said plug adjacent to the outer end of the connection

A⁴ and serves to lock the said plug against turning when in position. The plug B' should be so adjusted as to allow a small amount of play to the ball-valve B.

A short hollow tube D, having at one end a male connection D' and at its opposite end a female connection D⁰, has the said male connection D' engaged in the upper connection A² of the valve-body A and contains a ball-valve E, which normally closes the said male connection D', the latter being slightly reduced. Within the upper female connection D⁰ of the said hollow tube D is fitted a screw-plug F, having axial opening F⁰, similar to the plug B', hereinbefore described, and the said screw-plug F extends slightly into the hollow chamber E⁰ of the tube D. A coil-spring F', connected with the inner end of the plug F, bears upon the ball-valve E constantly when in position and tends to hold the said ball-valve upon its seat in the lower end of the hollow chamber E⁰. A lock-nut L, having an ear or lug L' thereon similar to the lock-nut C, hereinbefore described, is fitted upon the screw-plug F and serves to lock the same securely in position.

The operation of the valve is as follows: As the piston of the dash-pot descends the fluid in the dash-pot is forced into the chamber A⁰ of the valve-body A. This fluid under pressure will raise the ball-valve E from its seat against the action of the spring F', allowing the fluid to escape gradually through the upper connection of the valve and out through the central passage F⁰ of the screw-plug F, as will be obvious. At the same time this pressure of the fluid will force the valve B closely upon its seat, thereby preventing ingress of any portion of the fluid through the lower connection of the valve. Conversely, as the piston of the dash-pot ascends a partial vacuum is created within the chamber A⁰, which, communicating through the passages A⁵ in the partition-walls A⁴ with the chamber A⁵, lifts the valve B from its seat and allows gradual ingress of air or other fluid to the cylinder of the dash-pot to relieve the partial vacuum created as above described. This alternate action of the valves E and B is repeated each time the piston of the dash-pot descends and ascends, thus alter-

nately relieving the pressure and the vacuum created by the action of the dash-pot within the chamber A⁰ of the valve-body A.

Having thus described my invention, what I claim as new, and desire to secure by Letters Patent of the United States, is—

1. In a valve of the character described, the combination with the body of the valve having a hollow chamber and outlet and inlet connections, each having a hollow valve-chamber and an outer screw-threaded opening; of a screw-plug having an axial escape-passage therein engaging the screw-threaded opening in the outlet connection; a ball-valve in the chamber of said outlet connection; a coil-spring interposed between the inner end of said screw-plug and said ball-valve tending to hold the latter upon its seat; a screw-plug having an axial inlet-opening engaging the screw-threaded opening in the inlet connection, and said screw-plug having also a concave valve-seat at its inner end; a free ball-valve in the chamber of said inlet connection fitting the seat upon said screw-plug; and a stop at the inner end of the inlet-chamber for limiting the movement of the valve, substantially as described.
2. In a valve of the character described, the combination of the body A having hollow

chamber A⁰, integral inlet connection A² having valve-chamber a⁰ therein and screw-threaded opening a³, the screw-plug B' having axial inlet-passage B⁰ therethrough and concave valve-seat b⁰ at its inner end, the free ball-valve B in said chamber a⁰ fitting the said valve-seat and by gravity closing the inlet-opening; the internally-screw-threaded connection A², hollow tubular body D having a reduced male screw-threaded connection D' engaging the connection A² on the valve-body and forming interiorly a valve-seat, said tubular body having a screw-threaded opening D⁰; a ball-valve E in said tubular body, a screw-threaded plug F engaging said screw-threaded opening D⁰ and having an axial passage therethrough; and a coil-spring interposed between the inner end of said screw-plug F and said ball-valve E, tending to hold said valve closed against pressure from within the valve-body, substantially as described.

In testimony whereof I affix my signature in presence of two witnesses.

CHRISTIAN DORN.
